UNITED STATES PATENT OFFICE.

HENRY LAYTON FISHER, OF HAMILTON, ONTARIO, CANADA.

LUBRICATING SYSTEM.

1,315,919.

Specification of Letters Patent. Patented Sept. 9, 1919.

Application filed May 13, 1919. Serial No. 296,863.

To all whom it may concern:

Be it known that I, HENRY LAYTON FISHER, a subject of the King of Great Britain, and a resident of Hamilton, in the 5 Province of Ontario and Dominion of Canada, have invented certain new and useful Improvements in Lubricating Systems, of which the following is a specification.

My invention is an improvement in lubricating systems, and has for its object to provide a system of the character specified especially adapted for internal combustion engines, for thoroughly lubricating the crank shafts and the pistons, wherein the lubrication is brought about by the movement of the crank shaft.

In the drawings:

Figure 1 is a vertical section of a portion of an internal combustion engine provided 20 with the improved system;

Figs. 2, 3 and 4 are sections on the lines 2—2, 3—3 and 4—4, respectively, of Fig. 1.

Fig. 5 is a section similar to Fig. 4 showing a modified construction,

Fig. 6 is a section on the line 6—6 of Fig. 5.

In the present embodiment of the invention a circular trough 1 is provided for each two cranks 2 of the crank shaft 3, the said 30 troughs snugly encircling that portion 4 of the crank shaft which connects the two cranks 2. Each trough, as shown in Fig. 3, is sectional, and the sections have radial lugs 5 at their ends, which are secured to the crank case by bolts and nuts 6. Thus 40 that portion 4 of the crank shaft between the two cranks rotates within the trough, and scoops 7 are secured to the portion 4 at the ends thereof, these scoops having bases 8 which are secured to the portion 4 by screw bolts, as shown.

Each of these scoops dips into the adjacent trough, and scoops up the oil therefrom as the crank shaft rotates, and this oil 45 is fed through registering passages 9 and 10 in the scoop and in the portion 4, to a passage 11 which extends transversely of the said portion 4 and into the adjacent crank, the said passage being axial to the crank 50 and having a radial extension 12 which opens at the periphery of the crank, in the bearing 13 of the piston rod 14, which is connected to the piston 15 in the cylinder 16 in the usual manner.

Referring to Fig. 1, it will be noticed 55 that the passage 11 extends to that face of

the portion 4 which is remote from the crank, and a plug 17 is provided for normally closing the outer end of the said passage. Thus the oil may feed freely from the 60 scoop through the communicating passages 9, 10, 11 and 12 to the bearing on the crank.

Each piston rod 14 has a longitudinally extending cored passage 18 which communicates with a passage 19 in the crank pin 20 65 which connects the piston with the piston rod. This passage 19 extends longitudinally of the pin, opening at each end thereof, and by means of the passages 18 and 19 oil will be conducted to the periphery of 70 the piston to lubricate the piston and the cylinder.

A check valve 21 is arranged within the passage 18 near its connection with the bearing, and the valve is normally held 75 closed by a spring 22 which is arranged between the valve and a plug 23 threaded into an inclined opening in the piston rod, which communicates at its inner end with the passage. Referring to Fig. 1, it will be seen 80 that each of the bushings 24 of the cranks is recessed as indicated at 25 adjacent to the passage 18, to provide an oil space adjacent to the crank.

The oil pan 26 has the grooves 27 at the 85 cranks, and the usual pipe 28 connects the pan with the pump (not shown) for withdrawing the oil. As shown, this pipe 28 has a branch 29 for each of the grooves 27.

Referring to Fig. 4, it will be seen that 90 each of the passages 9 from the scoop 7 inclines outwardly in the direction that the crank is traveling, so that there is no impediment to the oil flow from the scoop to the passage 11. The oil passes into the 95 troughs 1 by way of a pipe 30, each trough having a pipe 30 for supplying the oil.

In operation, when the engine is running each crank and each piston is thoroughly 100 lubricated. The scoops 7 pick up the lubricant from the troughs, and the said lubricant flows through the passages 9, 11 and 12 to the bearings of the cranks. From here the oil flows through the passages 18 and 19 to the surface of the piston. The 105 surplus oil from the bearings is supplied to the cylinder walls and to the interior of the crank case, and this surplus is returned to the oil sump to be again strained and pumped to the bearings. The system gives 110 a low pressure, steady force feed of clean, cool oil to the bearings and cylinders. The

pressure on the check valve 21 may be regulated by means of the plug 23, thus allowing more or less oil to pass the valve, as may be desired. On the down stroke of 5 the piston the valve lifts, permitting a small quantity of lubricant to pass. It reseats on the up stroke and retains the lubricant taken, thus acting as a force pump to supply a steady stream of lubricant to the 10 wrist pin 20 and the cylinder walls. Only fresh oil is delivered to the crank and from thence splashed into the cylinder. The amount of oil fed to each pair of cylinders may be closely regulated by controlling the 15 amount of oil fed to the pump through the pipe 30.

In the embodiment of the invention shown in Figs. 5 and 6, the trough 31 corresponding to the trough 1 of Fig. 1 is arranged in 20 the same manner as the trough 1, but instead of the scoops with bases, the scoops 32 are connected with a ring 33 which is arranged concentric with the trough, engaging at its ends the ends of the element 4.

25 I claim:

1. In combination with the crank shaft, the cylinders, the pistons, the crank pins, and the piston rods connecting the crank pins with the cranks of the crank shaft, of a 30 common means for force feeding lubricant to the bearings of the piston rods and to the cylinder walls, said means comprising annular troughs encircling the crank shaft between each pair of adjacent cranks and 35 adapted to contain lubricant, the crank shaft having scoops moving within the trough, said shaft having passages leading from each scoop to the bearing of the adjacent crank, the piston rod and the crank pin 40 having longitudinally extending passages communicating with each other for leading the lubricant from the bearing of the crank to the cylinder walls, a spring controlled check valve in the passage of the piston rod, 45 and means for varying the pressure of the spring.

2. In combination with the crank shaft, the cylinders, the pistons, the crank pins, and the piston rods connecting the crank 50 pins with the cranks of the crank shaft, a common means for force feeding lubricant to the bearings of the piston rods and to the cylinder walls, said means comprising annular troughs encircling the crank shaft between each pair of adjacent cranks and 55 adapted to contain lubricant, the crank shaft having scoops moving within the trough, said shaft having passages leading from each scoop to the bearing of the adjacent crank, 60 the piston rod and the crank pin having

longitudinally extending passages communicating with each other for leading the lubricant from the bearing of the crank to the cylinder walls, and a spring controlled check valve in the passage of the piston rod. 65

3. In combination with the crank shaft, the cylinders, the pistons, the crank pins, and the piston rods connecting the crank pins with the cranks of the crank shaft, of a common means for force feeding lubricant 70 to the bearings of the piston rods and to the cylinder walls, said means comprising annular troughs encircling the crank shaft between each pair of adjacent cranks and adapted to contain lubricant, the crank shaft 75 having scoops moving within the trough, said shaft having passages leading from each scoop to the bearing of the adjacent crank.

4. In combination with the crank shaft, 80 the cylinder, the piston, the crank pin and the piston rod connecting the crank pin with the crank shaft, of a common means for force feeding lubricant to the bearings of the piston rod and to the cylinder walls, 85 said means comprising annular troughs coaxial with the crank shaft, said shaft having a scoop moving in the trough for supplying the oil to the bearings, the crank shaft, the piston rod and the crank pin having 90 communicating passages for conducting the oil, and a spring controlled check valve in one of the passages for preventing return of the lubricant.

5. In combination with the crank shaft, 95 the cylinder, the piston, the crank pin and the piston rod connecting the crank pin with the crank shaft, of a common means for force feeding lubricant to the bearings of the piston rod and to the cylinder walls, 100 said means comprising annular troughs coaxial with the crank shaft, said shaft having a scoop moving in the trough for supplying the oil to the bearings, the crank shaft, the piston rod and the crank pin having 105 communicating passages for conducting the oil.

6. In combination with the crank shaft, 110 of means for force feeding lubricant to the bearings of the shaft, said means comprising annular troughs coaxial with the crank shaft, the shaft having a scoop moving in the trough for supplying the oil to the bearings, said shaft having passages for conducting the oil to the bearings.
